UNITED STATES PATENT OFFICE.

ADDISON P. TRIMM, OF BUFFALO, NEW YORK

CLEANING DEVICE.

No. 811,001.

Specification of Letters Patent.

Patented Jan. 30, 1906.

Application filed December 15, 1904. Serial No. 237,027.

To all whom it may concern:

Be it known that I, ADDISON P. TRIMM, a citizen of the United States, residing at Buffalo, in the county of Erie and State of New York, have invented certain new and useful Improvements in Cleaning Devices, of which the following is a specification.

This invention relates to improvements in devices for cleaning lookout or head windows of cars, locomotive-cabs, and the like; and it has for its object to provide an effective device which can be readily operated from within to free the outside of the window from rain, dust, snow, and other substances, to provide simple means for simultaneously cleaning both the inner and outer sides of the window whereby the steam on the inner side may be cleaned off, to provide means for scraping the outer side of the window to free the same of ice or such other adhering matter which is impossible to remove with the cleaning rubber or pad, and to further improve on devices of this character in a manner to be hereinafter described.

My invention consists in the novel construction, arrangement, and combination of parts to be hereinafter described, and particularly pointed out in the appended claims.

In the drawings, Figure 1 is a perspective view of a portion of a car, showing my improved device applied thereto. Fig. 2 is an enlarged vertical section taken on line 2 2, Fig. 1. Fig. 3 is an enlarged horizontal section taken on line 3 3, Fig. 1. Fig. 4 is a vertical section through a portion of line 2 2, Fig. 1, showing the device canted to bring the metallic scraper in contact with the outer side of the window. Fig. 5 is a section taken on a plane indicated by line 5 5, Fig. 3. Fig. 6 is an inner elevation of a portion of the lookout-window and the frame therefor, showing the manner of holding the device elevated. Fig. 7 is a view of one end of the outer cross-head carrying the cleaner-pad and the metallic scraper.

Referring to the drawings in detail, like letters of reference refer to like parts in the several figures.

The letter A designates a car, and more properly the vestibule of a car, having a lookout or head window B, to which my improved device (designated by the letter C) is applied for the purpose of removing moisture, snow; sand, or other matter which might adhere to the outer side of the window and render the view of the motorman obscure. The frame

D of the window is provided with vertical slots E, lined with brass to provide smoothness and offer the least possible resistance to the operating-handles, to be hereinafter described.

A cross-head G extends horizontally across the lookout-window and is adapted to traverse the window in a vertical plane, it being carried by operating-handles H, which extend through the slots E and at their ends within the car are provided with removable grips h, which are secured to the handles by screws h' or otherwise. Throughout the greater portion of their length these handles are flat and slide freely within the slots E in order to quickly carry the cross-head to the bottom of the window and back. The outer ends of said handles are cylindrical and threaded and pass through holes h² near the ends of the cross-head from which they project, and onto the projecting ends I screw nuts h³ to securely fasten the cross-head to said handles. On the inner side of the cross-head, coincident with the holes h³, a rectangular socket h⁴ is formed to receive the flat portion of the handle adjacent the cylindrical end, which prevents turning of the handles on the cross-head. The cross-head G is provided on its inner side with a longitudinal groove I, in which a felt or rubber strip i is secured, so that one edge of the same is brought in contact with the window to free the same of rain, sleet, &c., when the cross-head is moved up and down to traverse the window. Said cross-head is also provided with a longitudinal groove on its upper side, in which a metallic strip J is secured, which strip is bent inward toward the window, with the free longitudinal edge thereof held out of contact with the window. At such times when the rain or sleet freezes to the window the device is canted, as shown in Fig. 4, which is done by pressing down on the handles to slightly turn the cross-head and bring the metallic strip or scraper against the window. On moving the device downward when in such position the window is quickly cleaned and an unobstructed view obtained, as both the metallic strip and the flexible strip bear against the window, as shown in Fig. 4—the metallic strip to loosen the ice and the flexible strip to remove the ice and clean the window simultaneously. I also provide a cross-head K within the vestibule or housing, which is provided with openings k to permit of its being placed on the handles and with set-screws k',

adapted to secure the same to the handles. This cross-head is also provided with a longitudinal groove k^2 , in which a felt strip k^3 is secured, said strip serving to be brought in contact with the inner side of the lookout-window to remove the steam from the same. By means of the set-screw k' cross-head K may be adjusted toward and from the window.

Normally the device is held elevated, in which position it is locked by suitable means (herein shown as pivoted stops L) which are turned to lie underneath the handles and across the slots E. When in this position, the stops are locked against movement by pins M, inserted into apertures m in the window-frame, thus preventing accidental lowering of the device while holding the same in readiness for use at all times.

To prevent the wind, rain, &c., entering the vestibule or housing when the device is elevated, each slot is covered by a strip of rubber N or other suitable material, one end of each strip being affixed to the cross-head G and the other end thereof being attached to the window-frame beneath the slot it covers. When lowering the device to clean the window, the strips loop themselves, as shown in Figs. 1 and 2, thus permitting free action of the device.

Having thus described my invention, what I claim is—

1. The combination with the wall of a housing having guide-slots therein, of a cross-head lying across the window of said wall, a cleaning device secured to said cross-head and lying in contact with the window, and handles at the ends of said cross-head and extending through said slots within reach of the operator within the housing.

2. In a device of the character described, the combination with the wall having guide-slots therein, of a cross-head normally held elevated and having handles extending through said slots to permit the device to be operated from within the housing, a cleaning device carried by said cross-head, and means for closing said slots when the device is in its normal position.

3. In a device of the character described, the combination with the wall having guide-slots therein, of a cross-head normally held elevated and having handles extending through said slots to permit the device to be operated from within the housing, a cleaning device carried by said cross-head, and flexible strips attached to said cross-head and to the wall beneath the guide-slots.

4. The combination with the wall of a housing having guide-slots therein, of a cross-head having cleaning devices comprising a cleaning-strip, and handles extending from the cross-head through said guide-slots to render the device operative from within the housing.

5. In a device of the character described,

the combination of a window-frame having guide-slots therein, a cross-head extending across the front of the window, handles secured to said cross-head and having a flattened portion extending into the housing through said guide-slots, and a cleaning-strip projecting from the inner portion of the cross-head and lying in contact with the window.

6. In a device of the character described, the combination of a window-frame having guide-slots therein, a cross-head extending across the front of the window, a cleaning device on said cross-head, handles secured to said cross-head and having a flattened portion extending into the housing through said guide-slots, and a cross-head carried on the handles within the housing and having a cleaning-strip in contact with the window.

7. In a device of the character described, the combination of a window-frame having guide-slots therein, a cross-head extending across the front of the window, handles secured to said cross-head and having a flattened portion extending into the housing through said guide-slots, a flexible strip projecting from the inner portion of the cross-head and lying in contact with the window, and a cross-head adjustable on the handles within the housing and provided with a cleaning-strip adapted to clean the inner side of the window.

8. In a device of the character described, the combination of a window-frame having guide-slots therein, a cross-head extending across the front of the window, handles secured to said cross-head and having a flattened portion extending into the housing through said guide-slots, a metallic strip projecting from the upper portion of the cross-head and normally out of contact with the window, and a cross-head adjustable on the handles within the housing and provided with a flexible strip adapted to clean the inner side of the window.

9. In a device of the character described, the combination of a window-frame having guide-slots therein, a cross-head lying across the front of the window and having a transverse opening at each end, each opening being enlarged and rectangular at the inner end thereof, a cleaning-strip attached to said cross-head, handles rectangular in cross-section and having reduced threaded ends, said reduced ends and the adjacent rectangular portion of each handle fitting said opening, and nuts secured to the projecting ends of said handles with the extremities of the reduced ends projecting from the cross-head.

In testimony whereof I have affixed my signature in the presence of two subscribing witnesses.
